(57) CLAIM

The ornamental design for a range hood, as shown and described.

DESCRIPTION

FIG. 1 is a front elevational view of the range hood. The top and bottom of the range hood shown in FIG. 1 forms no part of the claimed design.

The opposed sides of the range hood design shown in FIG. 1 forms no part of the claimed design.

The broken lines form no part of the claimed design.

The characteristic feature of the design resides in a series of panels positioned in the lower half of the front of the range hood shown.
